UNITED STATES PATENT OFFICE.

PHILIP W. MOORE, OF EVANSTON, ILLINOIS, ASSIGNOR TO THE P. & M. CO., OF CHICAGO, ILLINOIS, A CORPORATION OF ILLINOIS.

RAIL-ANCHOR.

1,070,978.

Specification of Letters Patent.

Patented Aug. 19, 1913.

Application filed November 4, 1910. Serial No. 590,662.

To all whom it may concern:

Be it known that I, PHILIP W. MOORE, a citizen of the United States, residing at Evanston, in the county of Cook and State 5 of Illinois, have invented new and useful Improvements in Rail-Anchors, of which the following is a full, clear, concise, and exact description, reference being had to the accompanying drawing, forming a part of 10 this specification.

My invention relates to rail anchors or anti-creeping devices of the type in which there is a wedging action under the rail, which wedging action increases in effectiveness 15 upon any tendency of the rail to creep.

Among the objects of my invention I aim to provide a rail anchor which shall be comparatively simple and inexpensive to manufacture, which may be readily applied to 20 rails of different widths of base, which shall be adapted to grip the rail flanges firmly and without slipping, which shall automatically tighten its grip on the rail upon any tendency of the rail to creep, and which 25 shall not work loose and possibly disengage itself from the rail when the forward pressure of the rail anchor against the adjacent cross-tie is removed, as occurs upon rearward movement of the rail.

30 The main features of the invention may be incorporated in a variety of structures.

For the purpose of illustration, I have shown in the accompanying drawings two embodiments which I consider practical and 35 adapted to present commercial needs, and which will serve to facilitate the description of the broad features of the invention.

Other embodiments than those illustrated are, of course, contemplated.

40 In the drawings:—Figure 1 is a top plan view of one form of rail anchor applied to a rail. Fig. 2 is a section on line 2—2, Fig. 1. Fig. 3 is a side elevation of the rail anchor as applied to a rail. Fig. 4 is a top plan view of another form. Fig. 5 is a section on line 5—5, Fig. 4. Fig. 6 is a side elevation of the form shown in Fig. 4. Fig. 7 is a perspective view of one of the parts.

50 Referring more particularly to the first form of rail anchor illustrated, there is shown the usual cross-tie 1, supporting the rail 2, having flanges 3, 3. The rail anchor proper comprises preferably two separable members 4 and 5. The member 4 is constructed preferably of malleable iron and

has a jaw 6 adapted to grip one of the flanges 3 of the rail, said jaw being reinforced by flanges 7. At one end of the member 4 there is a downwardly extending projection 8 adapted to engage the cross-tie 60 or other relatively fixed stop for the purpose of resisting the creeping tendency. This downwardly extending portion is preferably reinforced by a flange 9.

The portion of the member 4 which extends beneath the rail terminates in a downwardly extending wall or rib 10, which runs diagonally with respect to the longitudinal axis of the rail, as clearly shown in Fig. 1. This wall is slightly under-cut, as shown at 70 11, (see Fig. 2) for the purpose of increasing the hold of this member 4 on the other coöperating member 5 described hereinafter. The object of the diagonal arrangement of the wall 10 and surface 11 is to adapt the 75 device to rail bases of different widths and also to provide a wedging engagement of the parts beneath the rail. It is obvious that this wedging engagement may be effected by any diagonally arranged slot cut 80 in the under surface of the member 4 if desired, or by various other expedients.

The other rail gripping member 5 is constructed preferably of spring steel, although I do not limit myself to this material. This 85 member is provided at one end with a resilient rail flange gripping tongue 12 which, as shown more particularly in Figs. 1 and 3, is normally deflected from the main body portion of this member to a considerable degree, so that it may readily be deflected still more and sprung over the rail flange by means of a suitable tool. It is provided at its opposite end with a reduced portion 13 so as to provide suitable clearance as at 14, 95 for the member 4. (See Fig. 2.) It is also provided with an intermediate cut-away portion having walls 15, 16 and 17. The wall 15 is slightly under-cut to correspond to the coöperating under-cut surface 11 of 100 the member 4.

In order to assemble both members on the rail base, the member 4 is applied to one rail flange adjacent to a cross-tie, and the member 5 is then held in a position approximately at right angles to the length of the rail, but tilted from a vertical plane and caused to hook on to or engage the diagonal wall 10 of the member 4 approximately at the point intended as its final position; that 110

is to say, as far along the wedging surface toward the tie as circumstances will permit. In this position, the spring tongue 12 which is below and about parallel to the rail flange, 5 may be seized with a suitable tool and sprung over the rail flange into approximately final position. The relation of the parts as thus assembled, is shown in Fig. 1, in which it will be noticed that the projecting tongue 12 is directed toward the tie. The grip of the member 5 on the rail flange 10 is firm enough to hold said member on the flange in its position approximately at right angles to the length of the rail, so that upon any tendency of the rail to creep, the distant 15 end of this member will ride along the wedging surface of the opposite member and thereby still further increase the gripping of the anchor on the rail. The member 4 will simply be caused to press more firmly 20 against the adjacent cross-tie, but without perceptible longitudinal movement.

It is apparent that any substantial movement of the rail in the direction of the arrow 25 will be prevented as any tendency toward this movement causes an increased gripping of the rail by the anchor, due to the increased wedging under the rail. The gripping of the member 5 on the rail flange 30 is firm enough to prevent said member from jarring loose from its coöperating member when the rail as a whole withdraws the rail anchor from the tie, as sometimes occurs.

The provision of the slightly under-cut 35 surfaces 11 and 15, insures that the parts of the rail anchor will be firmly locked together and will be held in their closest position vertically, thereby reducing to a minimum the stresses to which these parts are subjected. It is apparent, however, that the device 40 would nevertheless be operative without the above features, although I consider their use an advantage.

In the modification illustrated in Figs. 4, 45 5; 6 and 7, the members 18 and 19 are similar in general outline to the corresponding members heretofore described. The member 18, however, is provided with an under-cut portion 20, provided with a notched or 50 ratchet surface 21. It is also provided with a downwardly extending tie-abutting portion 22, similar to that already described. The coöperating member 19 is provided 55 with a rail gripping jaw 23, which is shown arranged in the same plane as the main body portion of this member, although said jaw may be deflected at an angle, if desired. The opposite end of the member 19 is provided with a spring pawl 24 deflected slightly to 60 one side for the purpose of more readily coöperating with the ratchet surface 21. In assembling this modified form of rail anchor, a tool 25 may be conveniently used, having a hooked end 26 which embraces the 65 jaw end of the member 19. After applying

the member 18 to one flange of the rail, this tool 25 and the member 19 held thereby, may be slipped under the rail from the side to which the member 18 has already been applied. After the jaw 23 has engaged the 70 opposite rail flange, the tool may be forced in the direction of the arrow shown in Fig. 4, causing the pawl 24 to ride as far as possible over the ratchet surface 21 which, it will be observed, is preferably arranged as 75 the arc of a circle, although other curves may be employed. After the member 19 and particularly the pawl 24, has been forced toward the tie as far as possible by means of the tool 25, said tool is removed. In this 80 position, it will be apparent that any creeping of the rail will cause an increased grip of the various parts, whereupon the creeping will be stopped and further creeping prevented.

In both of the forms described above, there is a considerable advantage in the use of spring steel for one of the members, as this material is not only resilient, but is readily adapted for the configurations illustrated and possesses great tensile strength. As a result, the weight and cost of the rail anchor as a whole are appreciably reduced. However, the invention is not to be limited to the use of particular materials.

I desire not to limit myself to the above described embodiments or to the details of said embodiments, as they are selected merely by way of illustration.

It is apparent that I may employ any 100 suitable means for accomplishing the desired result as long as the structure falls within the scope of the appended claims.

What I claim as my invention and desire to secure by Letters Patent of the United 105 States is:—

1. A rail anchor comprising a plurality of means for engaging opposite flanges of a rail base, said means having connecting portions beneath said rail, one of said engaging means being constructed of resilient material adapting it to be sprung into position on the rail flange after being suitably connected to said other means.

2. A rail anchor comprising means for engaging opposite flanges of a rail, said means being adjustably connected beneath said rail, to adapt said anchor to different widths of rail base, one of said flange engaging means being formed of resilient material adapted to be sprung over the corresponding rail flange, after being suitably connected to said other means substantially in adjusted position.

3. A rail anchor comprising a member extending beneath the rail, a rail gripping jaw associated with each end of said member, said member having a diagonal adjustment with one of said jaws to adapt said rail anchor to rail bases of different widths, one 125 130

of said jaws being constructed of resilient material.

4. A rail anchor comprising a member extending beneath the rail, rail gripping jaws associated with said member, one of said jaws consisting of a clip member having an inclined face beneath the rail with which said member is adapted to coöperate, whereby relative longitudinal movement of said 10 clip member and said first member will cause increased gripping of the rail, the other of said jaws being constructed of resilient metal.

5. A rail anchor comprising a bar having a shoulder at one end, a rail engaging jaw having a wedging surface adapted to coöperate with said shoulder and provided also with a tie-abutting portion, said bar being provided at its opposite end with a rail 20 engaging jaw of spring steel.

6. A rail anchor comprising a spring steel member having a rail engaging jaw, said member being held normally at right angles with the rail by said jaw, a coöperating member comprising a rail gripping jaw having a tie-abutting portion and having a diagonally arranged shoulder portion which said first mentioned member engages, whereby creeping of the rail causes an increased 30 wedging of said shoulder.

7. A rail anchor comprising members provided with jaws adapted to grip opposite flanges of a rail, said members having a wedging connection under said rail, and one 35 of said members consisting of resilient material, whereby it may be first adjusted to said other member and then sprung into position on said rail.

8. A rail anchor comprising members provided with jaws adapted to grip opposite flanges of a rail, said members having a wedging connection under said rail, one of 40 said members being much narrower than the other at the said connection, whereby 45 said connection permits adjustment of said members to various widths of rail base.

9. A rail anchor comprising members provided with jaws adapted to grip opposite flanges of a rail, said members having a 50 wedging connection under said rail, and one of said members having a longer engaging surface than the other of said members at said connection, thereby said connection permitting adjustment to various widths of 55 rail base and relative movement longitudinally of said rail.

10. A rail anchor comprising two members each provided with a jaw adapted to grip a rail flange, said members having a

wedging engagement under said rail, one of 60 said members having a tie-abutting portion, the other of said members having its jaw constructed of resilient material, whereby said jaw may be sprung over said flange after said members have been adjusted in 65 proper relative position.

11. A rail anchor comprising two members each having means for gripping a rail flange, one of said members terminating under the rail in a downwardly extending 70 diagonally arranged wall, the other of said members consisting of a bar of resilient material and provided with a notch adapted to receive said wall, whereby relative movement of said members longitudinally of said 75 rail will cause an increased wedging engagement of one of the walls of said notch with said downwardly extending wall to increase the grip of both members on the rail flanges.

12. A rail anchor comprising two rail 80 gripping members, one of which has a resilient tongue adapted to be sprung over one side of the rail base, each of said members being provided with coöperating wedging surfaces under the rail, each of said wedging surfaces being under-cut to maintain firm engagement of the parts when assembled on the rail.

13. A rail anchor comprising two rail gripping members one of which is provided 90 with a jaw adapted to grip one of the rail flanges over a considerable portion of its length, the other of which comprises a substantially flat bar of metal having a notch at one end adapted to provide a jaw for gripping the other rail flange for a short 95 distance, each of said members being provided with means interlocking under the rail, whereby creeping of the rail causes a relative movement of said flat bar with respect to said other member to increase the grip of both jaws on said rail flanges.

14. A rail anchor comprising rail gripping members one of which consists of a bar of substantially flat metal having a recess at 105 one end whereby a projecting tongue is formed, said tongue being deflected at an angle from the main body portion of the bar, said bar having at the other end a notched portion for coöperating with the 110 other of said members.

In witness whereof, I have hereunto subscribed my name in the presence of two witnesses.

PHILIP W. MOORE.

Corrections in Letters Patent No. 1,070,978.

It is hereby certified that in Letters Patent No. 1,070,978, granted August 19, 1913, upon the application of Philip W. Moore, of Evanston, Illinois, for an improvement in "Rail-Anchors," errors appear in the printed specification requiring correction as follows: Page 3, lines 45-46, strike out the words "of said members"; same page, line 54, after the word "adjustment" insert the words *of said members*; and that the said Letters Patent should be read with these corrections therein that the same may conform to the record of the case in the Patent Office.

Signed and sealed this 1st day of December, A. D., 1914.

[SEAL.]

R. F. WHITEHEAD,
Acting Commissioner of Patents.
